Shaw-Walker Company, Muskegon, Mich., a
corporation of Michigan

Application December 5, 1938, Serial No. 244,018

2 Claims. (Cl. 211—133)

This invention relates to improvements in a transfer sorting cabinet, and consists of the matters hereinafter described and more particularly pointed out in the appended claims.

It is customary in business and other office practice to collect and assort papers temporarily according to alphabetical or other classification in a tray mounted upon a stand, and then to later transfer said papers as thus assorted to files at intervals, depending upon the accumulation of the papers in the sorting tray. When sorting the papers in the tray in the first place, the operator is generally seated, as at a desk at which he is working. But when the stand bearing the tray is moved to the files to which the assorted papers are to be transferred, it is generally inconvenient, if not impossible, for the operator to make such transfer when seated. A stand which supports the sorting tray at the correct height for use from a seated position is too low for convenient use from a standing position.

The object of this invention is to provide a transfer cabinet including a sorting tray for use by a seated operator and for use when the operator is standing.

The advantages of the invention will appear more clearly as I proceed with my specification.

In the drawing:

Figure 1 is a perspective view of the novel transfer cabinet with the sorting tray in position for use by an operator when seated.

Figure 2 is a perspective view of said transfer cabinet with the tray in a higher position for use by an operator when standing.

Figure 3 is a view representing a vertical section through the transfer cabinet, with the tray in the position it occupies in Figure 1, the plane of the section being indicated by the line 3—3 of Figure 4.

Figure 4 is a section indicated by the line 4—4 of Figure 3, with the tray in position for use by an operator who is standing.

Figure 5 is a fragmentary detail section on an enlarged scale showing a device for maintaining the tray against horizontal displacement, when in either position.

Referring now to that embodiment of my invention illustrated in the drawing: 10 indicates a cabinet and 11 indicates a sorting tray. The tray is of familiar construction and is designed to receive and retain the familiar index guide cards and folders (not shown) in general use in filing systems.

The cabinet may be of any suitable construc-

tion and made of any desired material. Preferably, and as illustrated, the cabinet is made of sheet metal fabricated in any familiar manner to provide its parts hereinafter mentioned. It consists of an upright pedestal having sides 12, 12 braced apart and held in parallel vertical relation by means of vertically spaced members, preferably platforms or shelves, 13, 14 extending between. Said sides include upright bars 15, 16 which depend below the level of the lower shelf 13 to present legs for the pedestal mounted as shown on casters 17, 17 for convenience in moving the cabinet from place to place.

The tray 11 (which also is preferably made of sheet metal) has upright parallel side walls 11a, 11a and upwardly and outwardly inclined end walls 11b, 11b adapted to accommodate the files contained in the tray when shifted towards one or the other end of the tray for the insertion of papers into the folders contained therein. It has a bottom wall 11c. The end walls 11b are continued below said bottom wall 11c and are there bent at an angle to form supporting flanges 18, 18 extending parallel to and below the bottom wall 11c. Said supporting flanges are adapted to rest upon the platform 14 when the tray is in its lower position, as shown in full lines in Figures 1 and 3, and in dotted lines in Figure 4, and they are so spaced longitudinally of the tray as compared to the spacing of the sides 12, 12 of the stand that when the tray is disposed lengthwise at right angles to said sides 12 of the pedestal, the flanges will rest upon the top rails of said sides, as shown in full lines in Figures 2 and 4, and in dotted lines in Figure 3.

To maintain the tray against horizontal displacement when supported by the flanges 18 on said platform 14, the platform is provided near each side with fixed, spaced, rounded lugs 19 adapted to be engaged in correspondingly spaced apertures 18a in the supporting flanges 18 of the tray, as shown in full lines in Figure 3, and the top rails of the sides of the stand 12 are provided with similar fixed lugs 19a, 19a spaced correspondingly to the distance between the spacing of the apertures 18a when measured transversely of the tray, as shown in dotted lines in Figure 3. Said lugs may be formed in any convenient manner, and as shown herein, each consists of a bolt and nut secured to the platform 14 and to the rail of the side of the stand, with the head as shown in Figure 5 forming the lug 19 or 19a, as the case may be.

The operation of the transfer sorting cabinet will be obvious from the foregoing. When it is

to be used by one who is seated, as in first sorting the papers in the tray, the tray 11 is brought to rest with the supporting flanges 18 in engagement with the lugs 19 on the platform 14, as shown in Figures 1 and 3. When the contents of the tray are to be transferred to the files, and the operator is in a standing position, the tray is raised and turned at right angles and brought to rest with its supporting flange 18 engaged with the lugs 19^a, 19^a on the top rails of the sides 12, 12 of the stand, as shown in Figures 2 and 4. For convenience in lifting the tray, the end walls 11^b are provided with hand holes 11^c.

It will be noted that in the construction as illustrated, the side walls 11^a of the tray are somewhat greater in height than the distance from the top rails of the sides 12 of the pedestal to the supporting platform 14. As a result, said tray side walls 11^a stand above the level of the top of the pedestal. This is desirable, as otherwise the side walls of the pedestal might interfere with ready access to the contents of the tray.

While in describing my invention I have referred to several details of mechanical construction and arrangement, it is to be understood that the invention is not limited thereto except as may be pointed out in the appended claims.

I claim as my invention:

1. A cabinet comprising an upright pedestal having a vertically disposed compartment open at the top and at the front and rear sides of

said pedestal, means providing a stop defining the depth of said compartment, a sorting tray having a bottom wall, upright side walls and upwardly and outwardly inclined end walls, said tray being of a width to be inserted into the open top of said compartment in said pedestal, with its end walls disposed in the front and rear openings thereof and with its bottom wall supported on said stop means, and the bottom wall of said tray being of such length that when said tray is withdrawn from said compartment it may be disposed in position to bridge said compartment transversely with its ends supported upon said pedestal.

2. A cabinet comprising an upright pedestal having a vertically disposed compartment open at the top and at the front and rear sides of said pedestal, a horizontal shelf fixed within said pedestal below its top and defining the bottom of said compartment, a sorting tray having a bottom wall, upright side walls and upwardly and outwardly inclined end walls, said tray being of a width to be inserted into the open top of said compartment in said pedestal, with its end walls disposed in the front and rear openings thereof and with its bottom wall supported on said shelf, and the bottom wall of said tray being of such length that when said tray is withdrawn from said compartment it may be disposed in position to bridge said compartment transversely with its ends supported upon said pedestal.

JOHN H. PAGE.
